UNITED STATES PATENT OFFICE

1,973,093

GRIDDLE GREASING FORK

Joseph R. Moore, Denver, Colo.

Application August 21, 1933, Serial No. 686,097

2 Claims. (Cl. 65—12)

This invention relates to a fork-like device for use in greasing pans, griddles, etc. The principal object of the invention is to provide a fork-like structure which will securely hold a cloth dauber in place for griddle greasing purposes.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating a preferred form of the invention.

Fig. 2 illustrates the form of Fig. 1 with the cloth or dauber applied thereto.

Fig. 3 is a plan view illustrating an alternate form of the invention.

The preferred form of the invention comprises: a fork-like structure provided with tines 10 and a convenient handle 11. In the two outside tines 10, a plurality of small holes 12 are formed. In the heel portion of the tined extremity, one or more similar small holes 13 are formed. These holes do not interfere with the ordinary uses of the fork but adapt it for holding a cloth wrapping in place, such as indicated at 14. The cloth is wrapped one or more times around the tines and a thread 15 is stitched through the holes 12 and 13 to securely lock the cloth in place as shown in Fig. 2.

In the alternate form of the invention, the tines are omitted and a handle extremity 16 terminates in a relatively wide-relatively flat portion 17. The flat portion is provided with a series

of holes 18 and with two projecting ears 19 which are perforated as shown at 20. The ears project from the device so as to form wedge-shaped notches 21 adjacent the handle. This form is used similarly to the previously described form, that is, a cloth wrapping is wrapped about the extremity 17 and stitched through the openings 18 and 19. The ears 19 in this form serve to securely hold the cloth in place since the cloth automatically locks itself in the wedge-shaped notches 21 formed by the ears 19.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A pan and griddle greasing device comprising: a handled member; a relatively wide extremity on said handled member provided with perforations; perforated ears projecting outwardly from opposite sides of said wide extremity; a cloth wrapping surrounding said wide extremity; and a thread stitched through said wrapping and said perforations.

2. A pan and griddle greasing device comprising: a handled member; a relatively wide extremity on said handled member provided with perforations; perforated ears projecting outwardly from opposite sides of said wide extremity; a cloth wrapping surrounding said wide extremity; and a thread stitched through said wrapping and said perforations, said ears forming wedge-shaped notches which are engaged by said wrapping to hold the latter in place.

JOSEPH R. MOORE.
